US00D905081S

(12) **United States Design Patent** (10) Patent No.: **US D905,081 S**
Chaudhri et al. (45) Date of Patent: ** *Dec. 15, 2020

(54) **DISPLAY SCREEN OR PORTION THEREOF
WITH GRAPHICAL USER INTERFACE**

- (71) Applicant: **Apple Inc.**, Cupertino, CA (US)
- (72) Inventors: **Imran Chaudhri**, San Francisco, CA (US); **Jonathan P. Ive**, San Francisco, CA (US); **Tiffany Jon**, Sunnyvale, CA (US); **Woo-Ram Lee**, Sunnyvale, CA (US); **Wan Si Wan**, Sunnyvale, CA (US); **Christopher Wilson**, San Francisco, CA (US); **Chun Kin Minor Wong**, Cupertino, CA (US)
- (73) Assignee: **Apple Inc.**, Cupertino, CA (US)
- (*) Notice: This patent is subject to a terminal disclaimer.
- (**) Term: **15 Years**
- (21) Appl. No.: **29/665,704**
- (22) Filed: **Oct. 5, 2018**

Related U.S. Application Data

- (63) Continuation of application No. 29/583,597, filed on Nov. 7, 2016, now Pat. No. Des. 830,377, which is a continuation of application No. 29/466,602, filed on Sep. 10, 2013, now Pat. No. Des. 771,082.

CLAIM

The ornamental design for a display screen or portion thereof with graphical user interface, as shown and described.

DESCRIPTION

FIG. 1 is a front view of a display screen or portion thereof with graphical user interface showing the claimed design; FIG. 2 is a front view of another embodiment thereof; FIG. 3 is a front view of another embodiment thereof; and, FIG. 4 is a front view of another embodiment thereof. The broken lines in the figures show a display screen or portion thereof, and form no part of the claimed design.

1 Claim, 4 Drawing Sheets
